UNITED STATES PATENT OFFICE.

SETH B. ATWOOD, OF ROCKFORD, ILLINOIS.

ADJUSTABLE BUFFER AND ANTIRATTLER FOR DOORS.

1,269,575.

Specification of Letters Patent. Patented June 18, 1918.

Application filed November 17, 1916. Serial No. 131,847.

To all whom it may concern:

Be it known that I, SETH B. Atwood, a citizen of the United States, residing at Rockford, in the county of Winnebago and 5 State of Illinois, have invented certain new and useful Improvements in Adjustable Buffers and Antirattlers for Doors, of which the following is a specification.

This invention relates to buffers operable 10 between a door and its casing or jamb to cushion the closing impact of the door and also to prevent rattling or vibration thereof when closed and locked, and has more particular reference to the application of such a 15 buffer to automobile and other vehicle doors.

It is common practice to equip doors or door jambs of automobiles with one or more rubber or combined rubber and metallic buffers merely set in a rigid container or 20 attaching plate, but in the course of usage the fixedly positioned buffer becomes ineffective and entirely useless for the purpose for which it was provided, because of wear of the buffer and relative displacement of the 25 same in the door due to vibration and strains incidental to travel. Spring-cushioned buffers have also been employed, but have been ineffectual in that a spring of a tension suitable for a buffer is too weak to prevent rattling of a door in a practical manner. In 30 the instances that adjustable buffers have been provided, I have found that they have not been commercially practical and desirable because of objections to their construction, viz: that they have been too expensive 35 to manufacture, that the buffer is not maintained in proper relative relation to its co-operating parts, that in some instances the adjusting element projects through the casing or door to the outer side thereof, forming 40 a protuberance and marring the design of the body, and for other reasons known to automobile builders.

The primary object, therefore, of my invention is to provide an improved buffer and anti-rattler attachment for doors especially adapted for use on automobiles and vehicles, to overcome the objectionable features mentioned and to practically and effectively serve the purposes for which such buffers and anti-rattlers are designed.

In furtherance of this purpose, I preferably employ a solid rubber or similar resili- 55 ent material buffer and adjustably secure the same rigidly in an attaching plate or casing in a novel manner with the view to permitting adjustment of the buffer to greater or less projected positions in accordance with requirements, and to make such adjustments from a point readily accessible within the 60 sides of the door or its casing so that the adjusting element does not mar the outer design thereof.

Other objects and attendant advantages will be apparent as the invention becomes 65 better understood by reference to the following specification when considered in connection with the accompanying drawings, in which—

Figure 1 is a perspective view of a portion 70 of the door casing of an automobile body in the jamb of which is secured a buffer embodying my improvements;

Figs. 2 and 3 are face and side views, respectively, of the buffer detached from the 75 door jamb;

Fig. 4 is a horizontal sectional view centrally through the buffer, showing its relation to a door and its casing; and

Figs. 5 and 6 are detail views showing the 80 shape of the blanks which in this embodiment constitute the buffer casing.

In the present instance I have for purposes of illustration shown my improvements embodied in a buffer attached to the 85 door jamb of an automobile body and it should be understood that the improvements might be otherwise applied, or attached to the door. It might also be mentioned that in practice a pair of buffers are used for each 90 door, one being positioned adjacent to the top and the other the bottom of the door, or any number of buffers may be employed as conditions may require.

The casing or attaching plate carrying the 95 buffer and providing a means of attachment to the casing or door as the case may be, may be in the form of a plate shown in blank in Fig. 5 and consists of portions 7 and 8, the latter of which is provided with a rectangular buffer opening 9 and is bent at right angles to the portion 7 in conformity with 100

the edge or corner of a door jamb in which the plate is to be fitted. An additional casing portion is provided for forming with the plate mentioned a housing to incase the greater portion of the buffer and for other purposes as will be presently apparent. This casing portion may be formed integrally with or separate from the plate, and in the latter instance, may be pressed from the metal face of a door or door jamb. In the present instance, however, it is shown separate from the plate and shaped as shown in Fig. 6, in the form of a body 11 having opposed sides 12 adapted to be bent as on the dotted lines, to form the top and bottom walls of the buffer housing and provided respectively with reduced extensions 13 adapted to fit in narrow slots 14 in the plate portion 7 and riveted therein, and an end portion 15 forming the end of the casing. This merely shows one simple and practical manner of forming the buffer casing and the invention is in no way limited to this particular construction, since the casing may be made in various ways. The casing may also be suitably set in and secured to a door jamb or a door, and in the drawing it is shown as secured in a door jamb 16 of the door casing of an automobile body and secured thereto by means of wood screws 17, or any suitable means may be employed for the purpose.

The buffer, or resilient material, preferably of a suitable grade of rubber, is in the form of a block designated by reference character 18. The buffer block, opening 9, and housing 11 are preferably shaped so that the buffer fits snugly within said housing, projecting through said opening and is slidably lengthwise therethrough so as to project a greater or less distance from the face of the attaching plate. It will be noted, however, that in the present instance the housing 11 is shaped to inclose an additional part 19 in the form of a flat nut which lies intermediate the wall 11 and buffer and is confined against edgewise movement by the contiguous walls of the casing. When the nut is drawn toward the side 7 of the casing by means of a screw the buffer block will be rigidly clamped to the casing and firmly held in fixed connection therewith and against displacement in any direction. A screw employed for this purpose, designated by reference character 21, extends through an opening 22 in the casing portion 7, passes through an elongated slot 23 in the buffer block, parallel with the direction with which said buffer block is movable through the opening 9, and is threadedly engaged with the nut 19, as clearly shown in Fig. 4. The face of the nut 19 engaging the buffer block may be knurled so as to more firmly grasp and hold the same in a set position. From the foregoing

it will be apparent that by loosening the screw 21 the buffer block may be moved lengthwise in its casing and projected more or less from the face of the casing and then secured rigidly in such projected position by tightening the screw. The manner in which a door 24 engages the buffer is shown in Fig. 4, and it will be evident that my improved buffer may be mounted equally well upon a door or upon the door jamb, although the particular construction and type of these parts is determinative of the position of the buffer.

It will be noted that the construction affords a means wherein the adjustable element is located within the side walls of the door and its casing so that the buffer and its co-operating parts are entirely concealed when the door is closed and do not in any way mar the design or form any facial obstruction to an automobile. Furthermore, it is a comparatively simple matter to make the adjustment and it is a very important matter to adjust the buffer block from time to time as the same becomes worn or the door and its casing becomes slightly displaced because of strains to which they are subjected during usage. Otherwise, it is found that the door when locked will soon rattle and be a source of annoyance. By providing a buffer block of resilient material adjustably mounted in a casing or attaching plate so as to be adjustable and providing means for rigidly securing the buffer block in any of its adjusted positions by a clamping action, a very simple and inexpensive structure is obtained and one which very effectually and satisfactorily meets the practical requirements of a device of this character.

While I have shown one particular embodiment of my improvements, it should be understood that various changes and modifications might be made without departing from the spirit and scope of the invention as expressed in the appended claims.

I claim:

1. A buffer and anti-rattler attachment for doors comprising an attaching plate having an opening therein, a buffer slidably movable through said opening and having an elongated slot substantially parallel in the plane with which the buffer is movable, a screw passing through said slot and associated with the attaching plate, and a part associated with the screw and so arranged with respect to the buffer as to clamp the same rigidly to the attaching plate by turning the screw.

2. A buffer and anti-rattler for doors comprising a door or door jamb casing shaped to receive a buffer member, one end of which is adapted to project from the casing, an elastically yieldable buffer member posi-

tioned in said casing and movable relatively thereto to project more or less therefrom, the buffer member having an elongated slot coincident with its plane of movement, a screw-threaded member passing through

5 said slot, and a member associated with the

screw-threaded member and the buffer member and adapted upon turning of the screw member to tighten or loosen the buffer member in the casing in any adjusted position of 10 the buffer member therein.

SETH B. ATWOOD.
